UNITED STATES PATENT OFFICE.

FRANK O. HOAGLAND, OF HARTFORD, CONNECTICUT, ASSIGNOR TO PRATT & WHITNEY COMPANY, OF NEW YORK, N. Y., A CORPORATION OF NEW JERSEY.

LIMIT-GAGE.

1,323,280.

Specification of Letters Patent.

Patented Dec. 2, 1919.

Application filed January 19, 1918. Serial No. 212,596.

To all whom it may concern:

Be it known that I, FRANK O. HOAGLAND, a citizen of the United States, residing at Hartford, in the county of Hartford and 5 State of Connecticut, have invented certain new and useful Improvements in Limit-Gages, of which the following is a specification.

As heretofore commonly constructed, limit 10 and other gages have been forged or otherwise formed from solid metal. Gages of this type are entirely satisfactory in small sizes but for the larger sizes they are open to objection because of the relatively great 15 weight which is necessary in order to provide the required strength and rigidity. The principal object of the present invention is to provide a gage which can be constructed in large sizes and which will have the required strength and rigidity without having 20 the excessive weight which has heretofore been deemed necessary. This object I attain by making the body part of the gage tubular in form in order to provide the maximum 25 strength in proportion to the weight. Another object of the invention is to provide improved means for mounting and securing the measuring contacts. Further objects of the invention will be apparent from the following specification and claims.

In the accompanying drawing I have shown the embodiment of the invention which I now deem preferable, but it will be understood that various modifications and 35 substitutions of equivalents can be made without departing from the spirit of the invention as set forth in the claims appended to this specification.

Of the drawing:

40 Figure 1 is a plan view of a gage embodying the invention.

Fig. 2 is a side view with a part broken away.

Fig. 3 is a front view.

45 Fig. 4 is a sectional view on an enlarged scale taken along the line 4—4 of Fig. 1, the measuring contacts and securing devices therefor being removed.

50 Fig. 5 is a view similar to Fig. 4, showing one of the measuring contacts and the corresponding securing devices in place.

Referring to the drawing, 1 represents the main body of the gage which is constructed from a metallic tube. The tube is bent into 55 a U-shaped form, as shown, and it is flat-

tened at opposite sides to provide flat walls 2 and 3. Except at the ends, the metal of the tube extends in uniform semi-circular curves between the flat walls 2 and 3, thus providing an oblong cross section with 60 rounded ends. At its ends the tube has two straight sections which are parallel and which have opposed inner flat walls 4 and 5 extending perpendicularly between the walls 2 and 3 thus providing a rectangular cross 65 section. The outer wall of each end section of the tube is preferably bent inward to form a recess as indicated at 6 in Fig. 4. The ends of the tubular body are closed, preferably by means of flat plates 7 and 8 70 which are held in place in any suitable manner, as for instance by a brazing. The edges of the plates 7 and 8 are rounded to eliminate sharp corners or angles.

Carried by the parallel end sections of the 75 gage body are pairs of opposed measuring contacts. As illustrated, there are three such pairs 9, 9, 10, 10 and 11, 11. For each pair of contacts the inner and outer walls of the body at 4 and 6 are provided with aligned 80 apertures 12 and 13. Each aperture 12 is smooth and each aperture 13 is slightly larger than the corresponding aperture 12 and is suitably threaded. Each measuring contact has a main cylindrical part, which 85 closely fits the aperture 12, and an enlarged outer threaded part which fits the threaded aperture 13. Each contact has a slot 14 or other means permitting it to be readily turned. By means of a screw driver fitting 90 the slot, the measuring contact can be adjusted to any desired position.

For locking each contact in adjusted position I provide a screw 15 which extends through apertures 16 and 17 in the side walls 95 2 and 3. The enlarged head of the screw fits the larger aperture 16 and the smaller threaded end of the screw fits the aperture 17 which is suitably threaded. The head of the screw is provided with a curved annular 10. surface which is adapted to press against and fit the cylindrical part of the corresponding measuring contact and thus when the screw 15 is tightened the measuring contact is locked against movement.

When three pairs of measuring contacts are provided, as shown, the central pair is adjusted so that the inner measuring surfaces thereof are separated by a distance exactly equal to the normal or nominal size 110

of the pieces to be gaged. The two outer contacts are adjusted so that their inner measuring surfaces are at a slightly greater distance apart, this greater distance corresponding to the permissible amount which the pieces to be gaged may be over size. The two inner contacts are adjusted so that their inner measuring surfaces are at a slightly less distance apart, this lesser distance corresponding to the permissible amount which the pieces to be gaged may be under size. In the drawing these differences in distance are greatly exaggerated in order that they may be clearly seen. In use, the piece being gaged, in order to be acceptable, must permit the outer contacts to pass, but must not permit the inner contacts to pass. The central contacts may or may not pass, and these are primarily useful for setting the machine at exactly the correct adjustment.

While it is desirable to provide means whereby the gage may be adjusted for different sizes of work or for different limits, it is nevertheless essential that the gage be not changed by the workman who is using it or by any other unauthorized person. To prevent such unauthorized adjustment of the gage, I preferably fill the space at the outer ends of the measuring contacts with sealing wax, as indicated at 18. This sealing wax is molded to conform to the general outer contour of the body part of the gage and it therefore serves to provide a smooth outline as well as to prevent adjustment. If desired, the sealing wax may be impressed with a suitable seal which must be destroyed before any adjustments can be made. It will be clear that when adjustments are necessary the sealing wax is removed and the adjustments made by loosening the screws 15 and turning the contacts. After adjustment, the screws 15 are tightened and new sealing wax is put in place and impressed with the seal.

What I claim is:

- 45 1. A gage comprising in combination a tubular U-shaped body having a uniform oblong cross section with rounded ends throughout the curved portions thereof and having a rectangular cross section at the straight parallel end portions thereof, and opposed measuring contacts carried directly by the body at the said rectangular and parallel end portions thereof.
- 50 2. A gage comprising in combination a tubular U-shaped body, plates covering the ends of the body, and opposed measuring

contacts carried directly by the body independently of the plates.

55 3. A gage comprising in combination a U-shaped body which is tubular in form with thin walls in order to have the maximum strength in proportion to its weight, and opposed measuring contacts carried directly by the body at the opposite end portions thereof and extending through alined apertures in the inner and outer walls of the said end portions.

60 4. A gage comprising in combination a U-shaped body which is tubular in form with thin walls in order to have the maximum strength in proportion to its weight, and opposed measuring contacts carried directly by the body at the opposite end portions thereof and extending through alined apertures in the inner and outer walls of the said end portions, each of the said contacts being 70 rotatable and having threaded engagement with one wall and slidble engagement with the other wall.

65 5. A gage comprising in combination a U-shaped body which is tubular in form with thin walls in order to have the maximum strength in proportion to its weight, opposed measuring contacts carried directly by the body at the opposite end portions thereof and extending through alined apertures in the inner and outer walls of the said end portions, each of the said contacts being rotatable and having threaded engagement 75 with one wall and slidble engagement with the other wall, and locking screws respectively adjacent the measuring contacts and extending through alined apertures in the side walls of the said end portions of the body, each screw having threaded engagement with one wall and slidble engagement 80 with the other wall, and locking screws respectively adjacent the measuring contacts and extending through alined apertures in the side walls of the said end portions of the body, each screw having threaded engagement with one wall and slidble engagement 85 with the other wall, and locking screws respectively adjacent the measuring contacts and extending through alined apertures in the side walls of the said end portions of the body, each screw having threaded engagement with one wall and slidble engagement 90 with the other wall, and locking screws respectively adjacent the measuring contacts and extending through alined apertures in the side walls of the said end portions of the body, each screw having threaded engagement with one wall and slidble engagement 95 with the other wall.

95 6. A gage comprising in combination a tubular U-shaped body, and opposed rotatable measuring contacts extending through alined apertures in the inner and outer walls of the body and having threaded engagement respectively with the outer walls, the said outer walls being bent inward to form recesses adapted to retain bodies of sealing wax which cover the ends of the measuring contacts and prevent the contacts from being turned.

100 In testimony whereof, I hereto affix my signature.

FRANK O. HOAGLAND.
